UNITED STATES PATENT OFFICE.

JOHN A. WILLIAMS, OF BROOKLYN, NEW YORK, ASSIGNOR TO THE WILLIAMS AUTOMATIC MACHINE COMPANY, OF MOUNDSVILLE, WEST VIRGINIA.

VENDING APPARATUS.

SPECIFICATION forming part of Letters Patent No. 443,344, dated December 23, 1890.

Application filed July 28, 1890. Serial No. 360,200. (No model.)

To all whom it may concern:

Be it known that I, JOHN A. WILLIAMS, a citizen of the United States, residing at Brooklyn, in the county of Kings and State of New York, have invented certain new and useful Improvements in Vending Apparatus, of which the following is a specification.

My invention relates to vending-machines, and is designed primarily as an improvement on that represented in an application filed by me May 23, 1889, serially numbered 352,882.

In the drawings, Figure 1 is the bottom plan view of so much of a vending-machine as is necessary to illustrate the present invention. Fig. 2 is a longitudinal sectional view of the same on the line 2 2, with the parts in their normal position; and Fig. 3, a similar view showing the position the parts occupy after the coin has been inserted and the slide pulled outward to discharge one of the articles to be sold.

A indicates a supporting-frame for the operating-machine, which in the present instance is shown as made of a single casting. The frame comprises the plate B, having a coin-opening α , the block C, upon which the article to be sold rests, and parallel walls or guides D, which are grooved on their inner faces to receive the operating-slide E and the delivery-slide F, these parts being arranged substantially as shown in Patent No. 430,497, issued to me June 17, 1890, to which patent reference is hereby made for details not found herein.

The operating-slide E is provided with a coin-slot e , normally in alignment with the coin-slot α in the plate B, and the outer end of the said slide E is turned upwardly so as to form a handle by means of which the slide may be actuated.

Delivery-slide F is provided with an opening f near its front end, and in advance of the opening it is provided with a lug or projection g , the said lug or projection being located in advance of the arm K, secured to the under side of the operating-slide. A coiled spring G, connected at one end with the delivery-slide and at the opposite end with the removable back plate J, serves to hold the de-

livery-slide normally within the machine, 50 while a similar spring I, connected at its forward end to the operating-slide E (or its arm K) and at the rear to the upper end of a pivoted pawl or dog W, serves to hold the operating-slide also normally within the machine. 55

L indicates a pawl or dog pivoted to the inner face of one of the walls or guides D, and i a spring which extends from the pawl to a lug b, substantially as shown and described in 60 my pending application hereinbefore referred to. The pawl and its spring are shown in full lines in Fig. 1, and the pawl alone is shown in dotted lines in Figs. 2 and 3.

The pawl W is pivoted to one of the side 65 walls or guides D, and extends downwardly through a slot or opening α , formed in the delivery-slide F, as shown in all the figures.

From the foregoing description it will be observed that when the parts are in their normal position, as shown in Fig. 2, the lower end or tail of the pawl W will bear against the rear wall of the slot or opening α . When the actuating-slide E is pulled outward, the force of the spring I has to be overcome, and if the slide be released the spring I will return the slide to its normal position within the machine without effecting a discharge of the articles to be sold. When a coin is inserted into the machine, the slides E and F 70 will be locked together, as shown in Fig. 3, and as the two slides are pulled outward the pawl or dog W will be rocked or tipped, as shown in Fig. 3, against the tension of the spring I, and will, when the slide F has been 75 pulled outward far enough to eject an article, be found to be out of the slot or opening α . It will be observed, however, that as the lower end of the pawl W is moved forward the upper end will be carried backward, and as the pawl thus rocks or tips and the slide E is pulled outward, the spring I will be put under tension.

This forms in effect what I term a "variable resistance," the object of which is to prevent the surreptitious working of the machine by the insertion of lead or other soft metallic tokens. For it is clear that if the spring I be made comparatively strong con- 95

siderable force will be required to distend it, and as the token inserted into the machine is subject to a strain in locking the two slides together, the token will be broken and the 5 slides disconnected unless the said token be of the requisite strength.

No broad claim is made herein to a variable resistance as applied to a machine of this general character, for that is claimed in my 10 pending application, Serial No. 352,882, hereinafter referred to.

Having thus described my invention, what I claim is—

1. In a vending-machine, the combination, 15 with the frame or support, of an actuating-slide E and the delivery-slide F, adapted to be connected by means of a coin, a pawl W, working through a slot in the delivery-slide, and a spring I, connected at one end with the 20 actuating-slide and at the opposite end with the pawl W, all substantially as shown.

2. In an automatic vending-machine, the combination, with the frame or support A, of the actuating-slide E and the delivery-slide 25 F, adapted to be connected by means of a coin, a pawl W, pivoted at a point between its ends to the side wall of the frame or support and

projecting downwardly through a slot or opening x formed in the delivery-slide, and a spring I, secured at its forward end to the actuating-slide and connected at its rear end to the upper end of the pawl, all substantially as shown and described.

3. In a vending-machine, the combination, 35 with the frame or support A, of an actuating-slide E, a delivery-slide F, adapted to be connected with the actuating-slide by means of a coin and provided with a slot or opening x, and with a plain face in rear of said slot or opening, a pivoted pawl or dog W, projecting 40 downwardly through the slot or opening x, and a spring I, secured at its forward end to the actuating-slide and at its opposite end to the pawl or dog W, all substantially as shown, whereby when the delivery-slide is pulled 45 outward the pawl will be rocked and its lower end thrown out of the slot or opening onto the plain face of the delivery-slide.

In witness whereof I hereunto set my hand in the presence of two witnesses.

JOHN A. WILLIAMS.
